KNIFE

Kenneth M. Junker, Ellicottville, N. Y., assignor to Bur-
rell Cutlery Company, Inc., Ellicottville, N. Y., a cor-
poration of New York

Application April 30, 1954, Serial No. 30,262

Term of patent 14 years

(Cl. D22—3)

Fig. 1 is a side elevational view of a knife showing my new design; Fig. 2 is another elevational view showing the side opposite to that of Fig. 1; and Fig. 3 is a cross section thereof taken on line III—III of Fig. 1. The essential features of my design reside in the portions shown in solid lines on the drawing and the shaded portions of Figs. 1 and 2 are intended to show contrast.

I claim:

The ornamental design for a knife, substantially as shown and described
